UNITED STATES PATENT OFFICE.

JOSEPH W. KYLE AND JOHN W. HICKS, OF CHICAGO, ILLINOIS, ASSIGNORS
OF ONE-THIRD TO GARFIELD G. BENNETT, OF CHICAGO, ILLINOIS.

DOUBLE-ACTING EXPLOSIVE-ENGINE.

No. 809,451.

Specification of Letters Patent.

Patented Jan. 9, 1906.

Application filed December 17, 1902. Serial No. 135,593.

To all whom it may concern:

Be it known that we, JOSEPH W. KYLE and JOHN W. HICKS, citizens of the United States, and residents of the city of Chicago, in the 5 county of Cook and State of Illinois, have invented certain new and useful Improvements in Double-Acting Explosive-Engines; and we do hereby declare that the following is a full, clear, and exact description of the same, reference being had to the accompanying drawings, and to the letters of reference marked thereon, which form a part of this specification.

This invention relates more particularly to 15 explosive-engines of that class in which an explosion or impulse is given at each revolution of the shaft.

Heretofore in most explosive-engines valves having movable parts are employed in the 20 ports, which owing to the heat generated by the combustion of the gases frequently fail to operate satisfactorily, materially decreasing the efficiency of the engine.

The object of this invention is to provide a 25 compact and simple construction in which no valves are employed in positions subjected to heat.

It is also an object of the invention to provide improved means for generating and mixing 30 the gases of combustion and supplying the same in regulable charges to the cylinders at each revolution of the shaft.

The invention consists in the matters hereinafter described, and more fully pointed out 35 and defined in the appended claims.

In the drawings, Figure 1 is a side elevation of a device embodying our invention. Fig. 2 is a central vertical section of the same, taken longitudinally. Fig. 3 is an elevation 40 of the end opposite the generating and mixing devices. Fig. 4 is a central transverse vertical section showing the shaft in elevation. Fig. 5 is an enlarged top plan view of the charging and mixing means. Fig. 6 is a 45 vertical longitudinal section of the same. Fig. 7 is a transverse section thereof. Fig. 8 is an enlarged transverse section of the sparker. Fig. 9 is an end elevation of the same. Fig. 10 is a longitudinal section of the 50 relief-cylinder and a part of one of the engine-cylinders.

As shown in said drawings, said engine as shown is constructed double—that is to say,

with two cylinders, one above the other—and formed of two castings A and A', which, as shown, are cored out to provide inlet-chambers a a' and an exhaust-chamber a² and water-chambers a³ and a⁴, as shown in Fig. 2. The parts forming said casing or shell, as shown, are permanently and rigidly secured together 55 by means of bolts passing through the flanged edges of the same, and cylindric linings or bushings A² and A³ are provided longitudinally therein. Oppositely-reciprocating pistons C and C' are provided in each end of each 60 cylinder. Heads B and B' are provided at each end of the casing closing the ends of both cylinders and each provided with apertures and suitable stuffing boxes or glands b, concentric with the respective cylinders for the piston- 65 rods c c', which at their inner ends are each secured, respectively, in the piston-heads C C'. On the outer ends of the piston-rods at each 70 end of the engine are secured the cross-heads D D', respectively. Said cross-heads each comprise a vertical bar d, integrally connected 75 at its middle part at right angles with the laterally-projecting arms d' d'', the ends of which project beyond the sides of the engine-casing and are formed to provide journals for the connecting-rods E E and E' E'. A shaft F extends 80 centrally through and is journaled in said casing between the cylinders and on any suitable bearing F', disposed laterally thereof, and is provided beyond said bearing with a 85 suitable driving-wheel F², which also serves as a balance-wheel. A double crank (indicated as a whole by F³) is provided in said shaft in close proximity with the side of the 90 casing and between the same and the bearing F', and a similar double crank F³ is provided on the end of the shaft on the opposite side of the engine, and on the wrist-pins f f' f' of said cranks the inner ends of the connecting-rods E E' are journaled. The arrangement 95 of said cranks and the connection with the respective connecting-rods are such as to necessitate the pistons in each end of each of the cylinders reciprocating simultaneously and oppositely for the greater portion of their 100 travel, as shown in Fig. 2, and the crank-arms connecting the wrist-pins f f' of each crank are directed obliquely with the axis of the shaft F, thereby making it impossible for the connecting-rods to stop on centers. A 105 pipe G' leads from a generating and mixing

chamber (indicated as a whole by G) along the side of the casing and communicates at each end of the casing with the peripheral inlet chambers or passages a a' , of which the 5 passage a extends for a greater length longitudinally of the casing and is provided with a plurality of ports x , opening into each cylinder beyond the outermost travel of the pistons C', and a plurality of similar ports x' , positioned to open into the cylinders on the inner side of the pistons C' when in the same 10 position. The inlet-chamber a is comparatively narrow and provided with inlet-ports x^2 for each of the cylinders opening into the 15 cylinders at the outer end of each piston-head C when at the outer limit of their movement. Exhaust-ports y open from the cylinders into the exhaust-chamber a^2 at the inner side of the pistons C when at their outer limit of 20 movement, and an exhaust-pipe A⁴ communicates with said exhaust-chamber and acts to convey away the gases of combustion from the cylinders.

Many different forms of generating and 25 mixing devices may be employed. Preferably, however, the generating and mixing chamber is such as is shown in Figs. 5, 6, and 7, comprising a casing g, providing within the same a comparatively large mixing-chamber g' , communicating through a valved passage with a smaller chamber g^3 , which is in open 30 communication with the pipe G' and provided with a check-valve g^3 of any desired construction. A plurality of apertures are 35 provided in the top of the casing g above the mixing-chamber, beneath which is supported a conical screen of fabric, woven wire, or other suitable material, (indicated by g^2 .) A pump is provided on the top of the casing 40 comprising a cylinder g^3 , provided with a plunger g^4 therein normally held at the outer limit of its movement by means of the spring g^5 . A rod H is carried on the cross-head D' and provided at its outer end with a tipple-arm h, which engages the outer end of the plunger and actuates the same as the pistons 45 reciprocate. Two passages g^6 and g^7 communicate with the cylinder g^3 , each of which is provided with a ball-valve, that in the passage g^6 permitting gasoline or other hydrocarbon fluid to flow into the cylinder g^3 , while that in the passage g^7 permits the fluid to be 50 forced outwardly through said passage to fall upon the screen into the mixing-chamber g' , 55 where it is vaporized and passes into the chamber g^8 . The reciprocation of the piston acts to draw air through the apertures in the casing g and through the screen g^2 into the mixing-chamber, carrying therewith vaporized hydrocarbon, and into chamber g^8 and pipe G' into the inlet-chambers.

Obviously any desired igniter or sparker may be used. Preferably, however, an electrical sparker, such as that shown in Figs. 2,

4, 8, and 9, is used. Said sparker consists of 65 a shaft I, journaled in a sleeve i, provided with a peripheral flange at its inner end and which fits within and is insulated from the threaded sleeve i', flanged at its outer end by the sleeve i², of indurated hard rubber or other insulating material. A peripheral flange is provided on the inner end of said sleeve, which insulates the flange of sleeve i from the end of the sleeve i'. A washer i³, also of insulating material, is provided at the 70 outer end of the sleeve i'. A lever I², of fiber or other insulating material, is rigidly secured in the outer end of the shaft I, and nuts i⁷ i⁸ are provided on the outer end of said shaft and between which the end one of the conductor is secured. A tappet-arm I' is secured on the inner end of the shaft I, so that when the inner end of the sleeve i' is screwed 75 into the casing A' the tappet-arms I' extend within the respective cylinders, near the middle thereof. Each tappet-arm is provided with a contact-piece i⁹ for engagement with a part carried on the inner surface of one of the piston-heads. The lever I² on the outer end of said shaft normally contacts with an adjusting-screw i⁴, secured on the casing, as 80 shown in Fig. 9, and a spring i⁵ is engaged on said lever or arm i⁴ and acts to hold said arm normally in positive contact with said screw.

The operation is as follows: The engine being given its initial start in the usual manner, the tappet-arm h operates the pump and injects a portion of hydrocarbon into the mixing-chamber g, where it is vaporized and mixed with air, while the movements of the pistons inwardly serves to draw the explosive mixture through the passage g^7 and pipe G' into the inlet-chambers a and a' and through the ports x , x' , and x^2 into the outer ends of the cylinders behind the pistons. As the 90 pistons move outwardly toward the ends of the cylinders the charge behind the same and in the pipes G' are greatly compressed until the piston-heads reach the outward limit of their movement, in which positions the inlet-ports x' and exhaust-ports y are open, permitting the mixture compressed by the back stroke of the piston to flow into the space between the piston-heads and forcing the spent gas and products of combustion outwardly 95 into the exhaust-ports y, scouring the cylinders. The inward movement of the pistons now begins, immediately closing the inlet-ports x' and exhaust-ports y , and is continued compressing the mixture between the piston-heads until the pistons C', as shown, respectively, engage the contact-pieces on the tappet-arms I' of the sparker, producing a spark 100 in the combustible or explosive mixture between the pistons sufficient to ignite the same, whereby the explosion again forces the piston outwardly to the outer limit of their movement, again compressing the gas behind 105 the pistons C', as shown, respectively, engage the contact-pieces on the tappet-arms I' of the sparker, producing a spark 110 in the combustible or explosive mixture between the pistons sufficient to ignite the same, whereby the explosion again forces the piston outwardly to the outer limit of their movement, again compressing the gas behind 115 the pistons C', as shown, respectively, engage the contact-pieces on the tappet-arms I' of the sparker, producing a spark 120 in the combustible or explosive mixture between the pistons sufficient to ignite the same, whereby the explosion again forces the piston outwardly to the outer limit of their movement, again compressing the gas behind 125 the pistons C', as shown, respectively, engage the contact-pieces on the tappet-arms I' of the sparker, producing a spark

the same, injecting a new charge into the cylinders between the pistons. Obviously inasmuch as the pistons in opposite ends of the cylinders move oppositely simultaneously 5 and inasmuch as the cranks are arranged slightly obliquely with the center of the shaft it is impossible for said cranks to be arranged on center in such a manner as to prevent the explosive charge from having the desired effect. It is also to be observed that no valves 10 provided with moving parts are employed in any part of the device exposed to the action of heat and that the engine is perfectly balanced, the impulses being always exerted 15 equally and oppositely, thus minimizing vibration and irregularity of operation. Furthermore, it is obvious that if preferred the ports may be so arranged as to enable the initial compression of the charge to be made 20 between the pistons and the explosions to be made simultaneously at the ends of the cylinders, or, in other words, the exact reverse of the construction shown.

As a further improvement the relief-cylinder M is provided on the casing at the end 25 opposite the exhaust-ports and provided with a piston N therein, between which and the head m of the cylinder a strong spiral spring n engages. A port n' opens into said cylinder, which connects with the ports x and x', as shown in Fig. 10. When the relief-cylinder 30 is used, the compression of the mixture by the back stroke of the pistons C C' compresses the spring n, storing the energy of the 35 back stroke of the piston, so that when the port x' is opened the mixture is forced therethrough not only by its own expansion, but also by said piston N, thus immediately obtaining a desired compression in the ignition 40 portion of the cylinders.

Any arrangement also of water-jacket or other means for keeping the cylinders cool 45 may be employed. We have also provided oil-cups K for each of the cylinders, which may be of any desired type or construction, which communicate through passages k k' with the interior of both cylinders acting to 50 discharge oil or grease thereinto during the operation of the device. If preferred, the cylinders instead of being arranged one above 55 the other may be arranged side by side, and a greater or less number of cylinders may be employed, as preferred, and many details of construction may be varied without departing from the principles of our invention.

We claim as our invention—

1. An explosive-engine comprising a cylinder, simultaneously reciprocating pistons in each end thereof, a generating and mixing 60 device, a pipe leading therefrom and opening into each end of the cylinder beyond the outermost travel of the pistons, an inlet-port in open communication with the pipe and disposed between the pistons when at their 65 outermost limit of movement, an exhaust-

port also opening between the pistons when so positioned, a sparker positioned to ignite the charge when the pistons are at their inward limit of movement, a transverse shaft intermediate the ends of the cylinder, a plurality of oppositely-disposed cranks thereon and means connecting the outer ends of said pistons with said cranks and adapted to rotate said shaft. 70

2. The combination with a cylinder, of simultaneously and oppositely reciprocating pistons in each end thereof, unvalved communicating ports opening into each end of the cylinder beyond the outermost travel of the pistons, a like port opening between the pistons when in said position, means for supplying an explosive mixture through said ports into the ends of the cylinder which serve as compression - chambers and from thence between the pistons which in their inward movement compress the charge, a sparker disposed centrally of the cylinders and acting to ignite the mixture when under maximum compression, a transverse shaft, oppositely - disposed cranks thereon and a plurality of connecting-rods connecting said pistons with said cranks. 80 85

3. An explosive-engine comprising a two-part casing rigidly bolted together and cored to provide inlet-passages, an exhaust-passage 95 and a water-chamber, a cylindric bushing secured therein forming the engine-cylinder, oppositely and simultaneously reciprocating pistons in said cylinder having outwardly-extending piston-rods, a shaft disposed transversely of the pistons, a crank-arm on each end thereof, a cross-head on each of the piston-rods, and a connecting-rod secured on each end of each cross-head and operatively connected with the crank on each side of the 100 engine. 105

4. An engine comprising a cylinder having a cast-metal jacket or casing surrounding the same and cored to provide an inlet-passage at each end of the same, an exhaust-passage 110 intermediate of the ends, communicating water-passages surrounding the cylinder, oppositely and simultaneously reciprocating pistons in each end of the cylinder which act to compress the explosive mixture at the outward movement and compress the charge on the inward movement, and a centrally-disposed sparker acting to ignite the charge at maximum pressure, a transverse shaft having a double crank on each side of the cylinder and a cross-head at each end of the cylinders and reciprocated by the pistons and connecting-rods on each side of the cylinders engaged on each end of each cross-head and connecting the same with the cranks. 115 120

5. The combination with two parallel cylinders, of a transverse shaft extending centrally between the same, a double crank on said shaft on each side of the cylinder, a reciprocating piston in each end of each cylinder- 125 130

der the piston-rods of which extend through the cylinder-heads and are rigidly connected at each end by a cross-head, a connecting-rod journaled on each side of each cross-head and connected with the cranks on said shaft on each side of the cylinder, ports arranged to admit the explosive mixture into the ends of the cylinders for initial compression and between the pistons for final compression and 10 a spark in each cylinder extending between the pistons.

6. In a double-acting engine the combination with parallel cylinders of oppositely and simultaneously reciprocating pistons in each 15 end of each, a cross-head rigidly connected with the piston-rods at each end of the cylinders, a shaft extending centrally and transversely between the cylinders and provided on each side of the engine with a double 20 crank, one of which is set obliquely with respect to the shaft and connecting-rods journaled on each side of each cross-head connected at their inner ends on said cranks.

7. In an engine the combination with pistons 25 reciprocating oppositely in pairs, of a cross-head at each end of the engine, each rigidly connected with a plurality of the pistons, a connecting-rod on each side of each cross-head, a shaft having a plurality of double cranks thereon with which the connecting-rods engage and means for reciprocating the pistons.

8. In an engine the combination with pistons 35 reciprocating oppositely in pairs, of a cross-head at each end of the engine, each rigidly connected with a plurality of the pistons, a connecting-rod on each side of each cross-head, a shaft having a plurality of double cranks thereon with which the connecting-rods engage and means for injecting and compressing an explosive mixture between the pistons and means for exploding same.

9. In a device of the class described the combination with oppositely-reciprocating 45 pistons, the cross-heads, shafts and connecting-rods, of a generating and mixing device positioned near one end of the cylinder, a pump operated from one of the cross-heads and acting to force fluid hydrocarbon into the 50 generating and mixing chamber and means for regulating the action of the pump.

10. In a device of the class described the combination with oppositely-reciprocating pistons, the cross-heads, shafts and connecting-rods, of a generating and mixing device positioned near one end of the cylinder, a pump operated from one of the cross-heads and acting to force fluid hydrocarbon into the generating and mixing chamber and 60 means for regulating the action of the pump.

11. The combination with an engine-cylinder having oppositely-reciprocating pistons 65 therein, of a generating-chamber, a pump positioned and connected to force hydrocarbon fluid into the generator at each stroke of the piston in regulable amounts, a tappet-arm carried on one of the cross-heads and adapted to actuate the pump, a valved pipe leading from the generating-chamber longitudinally of the cylinders and unvalved ports 70 opening therefrom into the cylinders at each end thereof whereby the inward movement of the pistons acts to draw the explosive fluid into the ends of the cylinders.

12. The combination with an engine-cylinder 75 having oppositely-reciprocating pistons therein, of a generating-chamber, a pump positioned and connected to force hydrocarbon fluid into the generator at each stroke of the piston in regulable amounts, a tappet-arm 80 carried on one of the cross-heads and adapted to actuate the pump, a valved pipe leading from the generating-chamber longitudinally of the cylinders and unvalved ports opening therefrom into the cylinders at each end 85 thereof whereby the inward movement of the pistons acts to draw the explosive fluid into the ends of the cylinders, and a port opening between the pistons and acting to admit the fluid therefrom between the pistons. 90

13. In an explosive-engine the combination with two cylinders located one above the other, of a simultaneously and oppositely reciprocating piston in each end of each cylinder, cross-heads connecting the outwardly-extending ends of the piston-rods thereof, laterally-directed arms on each cross-head, a shaft extending centrally and transversely between the cylinders, a double crank on each end thereof, a connecting-rod journaled 100 on each of the projecting arms of each cross-head and each connected at their inner ends with the respective cranks on said shaft. 95

14. In an explosive-engine the combination with two cylinders located one above the other, of a simultaneously and oppositely reciprocating piston in each end of each cylinder, cross-heads connecting the outwardly-extending ends of the piston-rods thereof, laterally-directed arms on each cross-head, a 110 shaft extending centrally and transversely between the cylinders, a double crank on each end thereof, a connecting-rod journaled on each of the projecting arms of each cross-head and each connected at their inner ends 115 with the respective cranks on said shaft, means for admitting explosive mixture between the pistons in each cylinder and compressing the same by the inward movement of said pistons and a spark disposed between the pistons and each cylinder and acting to release the fluid when at maximum compression. 120

15. The combination in an explosive-engine, of a plurality of parallel cylinders 125 located one above the other, a shaft extending transversely between the cylinders, a double crank on each end thereof, said double cranks

being arranged with their centers out of alignment with the center of the shaft.

16. The combination with a plurality of cylinders, of a simultaneously and oppositely reciprocating piston in each end of each cylinder, a cross-head connecting the ends of the piston-rods at each end of the cylinders, laterally-projecting arms on each cross-head extending beyond the sides of the cylinders, a shaft extending transversely between the cylinders a double crank on each end, connecting-rods journaled at their outer ends on the ends of said arms and at their inner ends on the respective cranks on said shaft, a generating and mixing device for hydrocarbon fluid operated from one of the cross-heads and unvalved passages and ports adapted to admit the explosive mixture into the ends of the cylinder during the inward movement of the pistons, to be compressed during the outward movement thereof and a passage connecting with the ends of the cylinders adapted to admit the same between the pistons under maximum pressure whereby inward movement of the pistons acts to complete the compression and means for igniting the charge when under maximum compression.

17. The combination with a plurality of cylinders, of a simultaneously and oppositely reciprocating piston in each end of each cylinder, a cross-head connecting the ends of the piston-rods at each end of the cylinders, laterally-projecting arms on each cross-head extending beyond the sides of the cylinders, a shaft extending transversely between the cylinders a double crank on each end, connecting-rods journaled at their outer ends on the ends of said arms and at their inner ends on the respective cranks on said shaft, a generating and mixing device for hydrocarbon fluid operated from one of the cross-heads and unvalved passages and ports adapted to admit the explosive mixture into the ends of the cylinder during the inward movement of the pistons, to be compressed during the outward movement thereof and a passage connecting with the ends of the cylinders adapted to admit the same between the pistons under maximum pressure whereby inward movement of the pistons acts to complete the compression, and electrically-operated sparkers disposed between the pistons of each cylinder and acting to ignite the charge.

18. In an explosive-engine the combination with a plurality of cylinders having in their ends oppositely-reciprocating pistons, a generating and mixing device connected with said cylinders and adapted to supply an explosive mixture into the ends of the cylinders during the inward stroke of the piston, a passage and ports permitting the escape of said mixture into the cylinders between the pistons when compressed by the outward stroke thereof, an electrically-operated sparkers in-

termEDIATE of said pistons comprising an insulated tappet-arm having at its inner end a conducting contact-piece adapted to make and break contact with one of the pistons, an electrical connection at the outer end of said sparkers and a driving-shaft extending transversely between said cylinders.

19. The combination with a cylinder of oppositely-reciprocating pistons in the ends thereof, means for admitting an explosive mixture into the ends of the cylinder during the inward stroke of the piston, a relief-cylinder connected by ports with said ends of the cylinders and adapted to permit the compression of the explosive mixture therein during the outward stroke of the pistons, an exhaust-port located between the pistons when at the outermost limit of their travel and ports leading from the relief-cylinder to a point intermediate of the piston and adapted to deliver the explosive mixture between the cylinders for final compression and combustion.

20. In an explosive-engine a relief-cylinder communicating with the compression ends of the explosion-cylinder, a passage and port leading therefrom and opening into the combustion-chamber when the fluid is under maximum compression, and a spring-pressed piston in said relief-cylinder acting to maintain uniform tension on the said explosive fluid when said passage and ports are open.

21. The combination in an explosive-engine comprising a cylinder having oppositely-movable pistons in the end thereof, a generating and mixing device connected to supply an explosive mixture into the ends of the cylinder during the inward movement of the piston, a relief-cylinder connected with the ends of the cylinder and a compression-cylinder connected with the ends of the combustion-cylinder, a spring-pressed piston-head therein acting to maintain approximately uniform tension on the fluid, a passage and ports leading therefrom and connecting with the combustion-chamber between the pistons when the same are at the outward limit of their stroke, an exhaust-passage also located between the pistons when so positioned and means whereby the charge is ignited at the maximum compression during the inward stroke of the piston.

22. In an explosive-engine the combination with a plurality of cylinders of a crank-shaft extending transversely between the same, a plurality of cranks on said shaft arranged in obliquely-disposed pairs, a piston in each end of each cylinder, rods connecting said pistons with said cranks a hydrocarbon-generator operated by the movement of the pistons and means for admitting hydrocarbon from the generator to said cylinders.

23. In an explosive-engine the combination with a plurality of cylinders of a shell in-

6
closing the same, a piston in each end of the cylinders, inlet-ports between the cylinder and shell at each end of the cylinder, an inlet and an exhaust port opening between the 5 pistons when at their outer limit of movement, transverse crank-shaft intermediate the cylinders, cranks thereon and means connecting said cranks with the outer ends of the piston-rods.

In testimony whereof we have hereunto 10
subscribed our names in the presence of two
subscribing witnesses.
